(57) **CLAIM**

The ornamental design for a bus shelter, as shown and described.

DESCRIPTION

FIG. 1—a front view of a bus shelter showing our new design;

FIG. 2—a rear view of the bus shelter;

FIG. 3—a right side view of the bus shelter;

FIG. 4—a left side view of the bus shelter;

FIG. 5—a top view of the bus shelter;

FIG. 6—a bottom view of the bus shelter;

FIG. 7—a front perspective view of the bus shelter; and,

FIG. 8—a rear perspective view of the bus shelter.

The broken lines shown in FIG. 6 illustrate portions of the bus shelter that form no part of the claimed design.
